COUNTERBALANCING MECHANISM FOR
STEAM LOCOMOTIVESJohn Kupka, Schenectady, N. Y., assignor to
Walter D. Maring

Application May 29, 1934, Serial No. 728,123

4 Claims. (Cl. 121—116)

This invention pertains to steam locomotives and more particularly to means for counterbalancing the reciprocating parts of a steam locomotive having two cylinders with main pins set 5 at an angle of ninety degrees.

In the counterbalancing arrangements heretofore employed the reciprocating masses of the driving mechanism of such steam locomotives are counterbalanced by providing balance weights 10 in the wheel centers so arranged that the horizontal component of the said revolving balance weights in the wheel centers counteracts, partially, the inertia effects set up by the periodic movement of the cross heads, pistons and piston rods as well as the main rods.

The inconvenience attendant upon this method of counterbalancing is a most pronounced increase in the track stresses at higher operating speeds.

20 Due to the fact that revolving masses are employed to counterbalance purely reciprocating masses, a free component acting at right angles to the path of the reciprocating masses appears. Said free component tends in a steam locomotive of conventional design to cause a periodic fluctuation in the driving wheel loads where such balance weights are provided. Since the magnitude of this additional track stress increases 25 with the speed of the locomotive, it is obviously necessary to restrict the maximum operating speed of the locomotive to a rate much below its capacity.

The object of this invention is to effect a counterbalancing of the reciprocating masses of such 30 steam locomotives without having to fear the harmful effect of the dynamic augment of the static axle load regardless of the operating speed. Another object is to effect a decrease of tire wear which is directly attributable to said dynamic 35 augment—which is often referred to as hammer blow.

According to this invention, the valve motion, which operates the piston valves of the locomotive, is rearranged to eliminate the balance 40 weights in the wheel centers as far as the purely reciprocating parts are concerned.

As has already been mentioned, it is necessary that the main pins of the locomotive be set at 45 ninety degrees with respect to each other and inasmuch as any valve motion to operate piston valves is derived by combining the movement of two eccentrics or their equivalents, one with a constant throw which is synchronous, as far as 50 movement and angle are concerned, with the 55 main pin while the other is set at ninety degrees

to the main pin and is provided with a variable throw or its equivalent in the shape of a variable travel, it is here proposed to make use of the main pin set-up of the main driving mechanism of the locomotive in the following manner. The eccentric arm or its equivalent, which is set at ninety degrees to its main pin and which heretofore has invariably been disposed adjacent the main pin whose valve events are directly controlled by said eccentric arm or its equivalent 10 is now transferred across the engine to the other side thereof without, however, changing its constant angular relationship with the main pin. It will be apparent at once that since the main pins of any conventional steam locomotive are 15 set mutually at ninety degrees, the new position of the eccentric arm or its equivalent in relation to the main pin at the other side of the locomotive can either be one of total opposition or, alternatively, one of complete juxtaposition. 20

Fig. 1 is a fragmentary elevational view of the right side of a locomotive, depicting a valve motion of the Walschaert type together with a portion of the right cylinder and one of the driving wheels; and 25

Fig. 2 is a perspective viewed from the left side of the locomotive—the boiler, driving wheels and frame being omitted in order to show more clearly the valve motions and other essential parts on both sides of the locomotive and their inter- 30 relations.

Ordinarily, the valve motion located on either side of a locomotive serves to operate the piston valve on the same side, but here that does not hold true. On the contrary, the principal parts 35 of the valve motions in the present case are each transposed to the side of the locomotive opposite their respectively associated piston valves. Thus, the principal parts of the valve motion illustrated in Fig. 1 operates the left hand piston valve— 40 the transposition being effected by means of a suitable cross-shaft.

In Fig. 1, 1 is a main pin on a right hand driving wheel; 2 is an eccentric arm carried by the same wheel and so disposed that the eccentric 45 pin 2 is located diametrically opposite the main pin; 3 is an eccentric rod having an enlarged portion 3a which is preferably formed with an internal cavity filled with lead to serve as a counter-balance weight; 4 is an expansion link of the 50 usual form; 5 a radius rod; 6 a lever arm attached to a cross-shaft 7 extending transversely of the locomotive; 8 is another cross-shaft likewise extending transversely of the locomotive; 9 is a lever arm attached to cross-shaft 8; 10 is the 55

usual combination lever; 11 a union link; 12 the right hand cross-head; 13 a link interconnecting the combination lever with the piston valve stem; 14 is an adjusting member on the piston valve stem; 15 is a suitable bracket for the cross-shaft bearings; 16 is a lifting bar; 17 the reversing shaft; 18 the reversing lever which is connected to the reverse gear in the cab; 19 the right hand piston rod and 20 the main rod interconnecting the cross-head and main pin.

10 In the perspective view, Fig. 2, the valve motion and other parts located on the left side of the locomotive and corresponding to like parts on the right side are identified by like reference numerals with prime marks added. Thus, the main pin on the right side is identified by reference numeral 1 while the left main pin is identified by numeral 1'.

15 In order not to obscure any of the parts, a clear showing of which is considered essential, the driving wheels and axle have been omitted in Fig. 2 and the right hand main rod is shown broken off near its main pin.

20 It will be observed that, on the whole, the modified valve motion is very similar to the conventional Walschaert valve motion. The physical differences consist in (1) the location of the eccentric pin at an angle of one hundred and eighty degrees to the main pin instead of ninety degrees; (2) the provision of an auxiliary weight on the eccentric rod and; (3) the provision of cross-shafts and lever arms for effecting the necessary transpositions.

25 The main pins on either side of the locomotive are disposed mutually at ninety degrees in accordance with conventional practice. Hence, the eccentric pin on each side is at ninety degrees to the main pin on the opposite side; and since the valve motions are, in part, transposed, it follows that the resultant piston valve sequences are identical with those obtained with the conventional arrangement. The whole purpose of this transposition is to enable putting the eccentric pin on each side at one hundred and eighty degrees to the main pin on the same side so that the motion of the eccentric rod and its auxiliary weight will be at all times in direct opposition to the motion of the horizontally reciprocating driving members including the piston, piston rod, cross-head and main rod. The object, as stated at the outset, is to counterbalance the inertia effect of these last mentioned reciprocating members without putting the necessary balance weights in the driving wheels and to do this in such a way as to avoid as far as practicable vertical reciprocation of the balance weights—thus eliminating or greatly reducing the hammer blow effect.

30 In the arrangement described a large part of the valve motion including particularly the eccentric rod and its auxiliary weight reciprocate in a generally horizontal plane. The auxiliary weight is located at that end of the eccentric rod having the least amplitude of vertical motion. There is, it is true, some vertical as well as horizontal reciprocation of the auxiliary weight and the former is theoretically detrimental; but its magnitude is relatively small and the greater part of the auxiliary weight is borne by the frame of the locomotive which is spring supported. The residual hammer blow effect due to the vertical reciprocation of the eccentric rod and auxiliary weight is relatively insignificant. It could, manifestly, be almost entirely eliminated by an obvious change of design, but to do so would introduce complications which it is desirable to avoid. A com-

promise design, such as that illustrated, approaching the ideal but falling a little short of it, is commercially preferable to the introduction of complications incidental to a realization of the theoretical ideal solution. In other words, it is not considered commercially feasible to so design and construct the mechanism that the auxiliary weight will move only in a straight horizontal path; and particularly is that true in applying the invention to existing locomotives. Of course, such refinements might be resorted to in designing new locomotives if the designing engineer were so disposed; but it is doubted that the gain would offset the added complication. That, however, is a matter of individual opinion and I am not 15 to be construed as disclaiming such alternative arrangements which come within the scope of my broad inventive concept.

20 It, doubtless, will be clear that the auxiliary weight 3a is not the only part of the moving mass which serves to counterbalance the horizontal inertia effect of the driving members. The eccentric rod as a whole and the expansion link, in part, contribute to the aggregate counterbalancing mass. On the other hand, those parts of 25 the valve motion which move in the same direction as the adjacent driving members contribute somewhat to the inertia effect to be counterbalanced.

25 While I have shown an auxiliary weight as a 30 distinct entity, it will be obvious that the necessary added mass could be incorporated into the design of the valve motion parts in such a way that it would not appear as a distinct entity. Also it will be apparent that the auxiliary weight 35 need not necessarily be incorporated as an integral part of the valve motion—although that is considered by far the most convenient and practicable arrangement.

30 Cross-shafts 7 and 8 are provided at their opposite ends with lever arms corresponding to lever arms 9 and 6 respectively—the lever arm at the remote end of cross-shaft 7 being connected with the combination lever on the left side of the locomotive and the lever arm on the remote end of cross-shaft 8 being connected to the radius rod on the left side. The valve motion parts comprising elements 10, 11, and 13, obviously, in each case are components of the valve motion operating the piston valve on their own 45 respective sides of the locomotive. Since these latter parts are components of the valve motion as a whole, it follows that the valve motions are not transposed in their entireties. Those parts which are transposed I choose to designate for 50 convenience of identification as the "principal parts" of the valve motion.

35 It is believed that anyone skilled in the art will be able to at least roughly calculate the amount of auxiliary weight needed to effect a 60 balance in any particular case; but in any event it can be determined by trial.

40 Inasmuch as the inertia effects are proportional to the square of the velocity it is highly desirable that the velocity of the opposing masses 65 be equal at all times. This means that the eccentric pin is preferably located at the same radial distance from the center of rotation of the driving wheels as the main pin. Any arrangement which would not afford equal velocities at 70 all times between the opposing masses would not maintain a balance at all speeds because the masses are of fixed value.

45 The present invention may, of course, be used with suitable modifications with other forms of 75

valve operating mechanisms and is, therefore, not to be construed as limited in its application to the Walschaert type of valve motion.

What is claimed is:

- 5 1. The combination in a steam locomotive of a driving wheel having a main pin, reciprocatory driving means connected with said main pin, an eccentric pin carried by said driving wheel and disposed diametrically opposite said main pin, and
10 a valve motion connected to said eccentric pin, said valve motion including a reciprocating counterbalancing mass arranged to move in a path which is at least approximately parallel to the path of said driving means and at all times
15 in directional opposition to said driving means.
2. In a steam locomotive, two steam cylinders disposed individually on opposite sides of said locomotive, a pair of driving wheels having a common axis of rotation and likewise disposed
20 individually on opposite sides of said locomotive, a main pin for each of said driving wheels individually, said main pins being disposed mutually at an angle of ninety degrees about the center
25 of rotation of said driving wheels, an eccentric pin for each of said driving wheels individually, each of said eccentric pins being disposed diametrically opposite its associated main pin along a line intersecting the axis of rotation of said driving wheels, piston valves for each of said cylinders individually, a pair of valve motions for
30 operating each of said piston valves individually, the principal part of each of said valve motions being disposed at the side of the locomotive opposite its associated piston valve, said principal parts including, in each case, an eccentric rod which is connected to the eccentric pin on the side opposite its associated piston valve, said valve motions each including a counterbalancing

mass, and reciprocatory driving means on each side of the locomotive interconnecting said cylinders and driving wheels, the aforesaid counterbalancing mass on each side of the locomotive being of a suitable magnitude to bring about a 5 substantial counterbalancing of the horizontal inertia effect of the said reciprocatory driving means on the same side of the locomotive.

3. The combination in a locomotive of a pair of steam cylinders disposed individually on opposite sides thereof, a piston valve for each of said cylinders individually, a pair of driving wheels having a common axis of rotation and disposed individually on opposite sides of said locomotive, main pins for said driving wheels individually, 10 disposed mutually at an angle of ninety degrees about said center of rotation, eccentric pins carried by said driving wheels individually and disposed in each instance at an angle of one hundred and eighty degrees about said center of rotation 15 to the main pin carried by the same driving wheel, and a valve motion interconnecting each of said eccentric pins with the piston valve for the cylinder on the opposite side of the locomotive.

4. In a steam locomotive, a steam cylinder, a driving wheel, reciprocatory driving means interconnecting said steam cylinder with said driving wheel, an eccentric pin carried by said driving wheel, and a valve motion including an eccentric rod, said eccentric rod being connected at one end 25 to said eccentric pin, and a lumped counterbalancing mass carried by said eccentric rod at a point remote from said eccentric pin, said counterbalancing mass, supplemented by the mass of said valve motion, being of such magnitude as 30 largely or wholly to counterbalance the horizontal inertia effect of said driving means.
